SPIRIT LEVEL

Sinclair T. Roberts, Philadelphia, Pa.

Application April 23, 1952, Serial No. 283,813

5 Claims. (Cl. 33—211)

1

This invention relates to spirit levels, and it relates more particularly to the construction and arrangement of the stocks of spirit levels, and to the mounting of the bubble cells therein.

Heretofore it has been customary to make the stocks of spirit levels of wood, which wood should be straight grained, free from knots, and well seasoned. It is becoming increasingly difficult to obtain wood of the proper quality and condition, and in most instances the manufacturers of spirit levels have to resort to the use of opaque enamels and other finishes to cover the more or less imperfect wood which must now be used if the level stocks are to be made of wood.

Stocks made of metal such, for example, as aluminum or the like, require expensive machine operations, involve difficulties of mounting the bubble cells, and many times the desired metal is not available.

The principal object of the present invention is to provide a spirit level of a novel construction, the stock of which may be made of extruded plastic or other suitably shaped pieces of material.

A further object of the invention is to provide a spirit level the parts of which may be inexpensively assembled, and which when so assembled, will be reasonably accurate.

A further object of the invention is to provide a spirit level having the bubble cells mounted therein in a novel manner which will obviate the necessity of adjusting the cells in the stock.

A further object of the invention is to provide a spirit level having bubble cells of a novel form which may be inexpensively made.

The nature and characteristic features of the present invention will be more readily understood from the following description, taken in connection with the accompanying drawing forming part hereof, in which:

Figure 1 is a side elevation of a spirit level embodying the main features of the present invention.

Fig. 2 is a horizontal section thereof, enlarged, taken on the line 2—2 of Fig. 1;

Fig. 3 is a transverse section, also enlarged, taken on the line 3—3 of Fig. 1;

Fig. 4 is a similar view, the section being taken on the line 4—4 of Fig. 1;

Fig. 5 is a similar view, the section being taken on the line 5—5 of Fig. 1; and

Fig. 6 is a view of the several parts of a preferred form of bubble cell, the parts being shown in separated relationship before they are united to each other.

2

It should, of course, be understood that the description and drawing herein are illustrative merely, and that various modifications and changes may be made in the structure disclosed without departing from the spirit of the invention.

The stock of the spirit level of the present invention comprises edge members 10, each having an outer working face 11. The side faces 12 of each member 10 are preferably beveled as indicated in Figs. 3, 4 and 5 of the drawing. Each of the edge members has an internal dovetail groove 13, and also a larger groove 14 to provide shoulders 15 along its inner face.

The central or web structure is preferably made of a plurality of pieces which, in each instance, would be one or more than the number of bubble cells mounted in the stock.

The pieces 16 of the web structure, at each end of the stock, each have one end squared as at 17 to provide the outer ends of the web portion of the stock, and the other or inner end 18 of each piece 16 of the web structure is shaped complementary to the particular shape of the cell member employed, which will be hereinafter more fully described.

Likewise, each of the intermediate pieces 19 of the web structure is shaped at its respective ends as at 20 complementary to the shape of the bubble cells at the respective ends thereof.

Each of the pieces 16 and 19 of the web structure is preferably flat as at 21 and with its edge portions 22 shaped complementary to the inner grooves 13 and 14 in the edge members 10.

The bubble cells are preferably made of two similar parts 30 molded of transparent plastic of the acrylic resin type, and each of said bubble cells has its perimeter 31 of non-circular shape when assembled.

Each bubble cell 30 may be of any non-circular shape, but preferably has an elliptical perimeter, as shown in the drawing, although any other non-circular form may be used which will be non-rotative in the stock when the level is completely assembled.

The preferred type of bubble cell is shown with the parts in separated relationship in Fig. 6 of the drawing and, as there shown, each part comprises side walls 32, each semi-elliptical in outline, and each part is shaped at its abutting portion to provide an internal barrel shaped cavity 33 adapted to contain the liquid to provide the bubble.

Each part of the bubble cell is provided at one end with a semi-circular groove 34 extending

from the internal cavity 33 to the exterior, thereby to provide a passageway through which the bubble liquid may be introduced after the two parts are cemented to each other, and which may then be sealed by means of a suitable plug 35 cemented in the passageway provided by the grooves 34.

On each side of each of the bubble cells there is preferably mounted a glass cover plate 36 which serves to prevent the relatively soft acrylic resin, of which the bubble cell is made, from being scratched in use.

The respective ends of the several pieces 16 and 19 of the web structure are shaped complementary to the bubble cell which is confined between said ends at desired locations.

In the manufacture of the levels of the present invention the bubble cells are first separately molded and assembled. The edge members of the stock are cut to the desired lengths, and the web pieces are cut to their required lengths and shaped at the ends thereof as hereinbefore set forth.

The web pieces of the stock are then brought together by sliding the same in the grooves of the edge members confining a bubble cell adjacent the ends of each pair of pieces of the web structure. The parts are cemented to each other.

However, the web portion of the stock may be made of a single piece of material, and the openings for the bubble cells may be cut therein, in which case it will of course be necessary that said openings for the bubble cells be shaped the same as the perimeters of the bubble cells which are to be placed therein.

It will be seen that, by the present invention, there is provided a simple, durable and efficient form of spirit level which may be inexpensively made, which when assembled will be of a permanent and lasting character, and which will not only be initially accurate, but will also maintain its accuracy throughout its useful life.

I claim:

1. A spirit level comprising separate edge members each provided with an outer working surface, and an inner web structure in dovetail engagement with the edge members, the inner web structure being provided with non-circular openings, and bubble cells positioned in said openings, each of said bubble cells being fixedly positioned in its opening by having its perimeter complementary to and fitting said opening.

2. A spirit level comprising separate edge members each provided with an outer working surface, and an inner web structure comprising a plurality of pieces in dovetail engagement with the edge members, the abutting ends of each adjacent pair of web pieces being shaped to provide non-

circular openings, and bubble cells positioned in said openings, each of said bubble cells being fixedly positioned in its opening by having its perimeter complementary to and fitting said opening in which it is positioned.

3. A spirit level comprising separate edge members each provided with an outer working surface, and an inner web structure comprising a plurality of pieces in dovetail engagement with the edge members, the abutting ends of each adjacent pair of web pieces being shaped to provide non-circular openings, and bubble cells positioned in said openings, each of said bubble cells being fixedly positioned in its opening by having its perimeter complementary to and fitting said opening.

4. A spirit level comprising separate edge members each provided with an outer working surface, and an inner web structure comprising a plurality of pieces in dovetail engagement with the edge members, the abutting ends of each adjacent pair of web pieces being shaped to provide non-circular openings, and bubble cells positioned in said openings, each of said bubble cells being fixedly positioned in its opening by having its perimeter complementary to and fitting said opening, and each of said bubble cells comprising molded transparent members secured to each other in a transverse plane and formed to provide an internal cavity to receive the bubble fluid.

5. A spirit level comprising separate edge members each provided with an outer working surface, and an inner web structure comprising a plurality of pieces in dovetail engagement with the edge members, the abutting ends of each adjacent pair of web pieces being shaped to provide non-circular openings, and bubble cells positioned in said openings, each of said bubble cells being fixedly positioned in its opening by having its perimeter complementary to and fitting said opening, and each of said bubble cells comprising a pair of molded transparent members secured to each other in a transverse plane and formed to provide an internal elongated barrel shaped cavity to receive the bubble fluid, said cavity having its longitudinal axis disposed in said plane.
